MARQUISSETTE WOVEN TEXTILE FABRIC

Otto Echinger, 1 Gottfried Fessmann Strasse,
Zell im Wiesental, Germany

Filed Sept 28, 1965, Ser. No. 87,211

Term of patent 7 years

(Cl. D92—1)

The figure is a top plan view of a marquisette woven textile fabric, showing my new design.

I claim:

The ornamental design for a marquisette woven textile fabric, substantially as shown.
